UNITED STATES PATENT OFFICE.

MICHAEL LIPTAK, OF MINNEAPOLIS, MINNESOTA.

FURNACE WALL.

Application filed April 7, 1924. Serial No. 704,620.

To all whom it may concern:

Be it known that I, MICHAEL LIPTAK, a citizen of the United States, residing at Minneapolis, in the county of Hennepin and State of Minnesota, have invented certain new and useful Improvements in Furnace Walls; and I do hereby declare the following to be a full, clear, and exact description of the invention, such as will enable others skilled in the art to which it appertains to make and use the same.

My present invention relates to furnace walls or walls adapted to stand high temperatures, and is particularly directed to certain improvements, which make possible replacements of the inner wall portion or section without disturbing or tearing down the outer or permanent wall portion or section, and in which a complete wall may be constructed entirely from commercial bricks, blocks or tiles, such as are carried in stock by and may be purchased from brick manufacturers or their sales agencies. Otherwise stated, the complete wall is made up of what may be termed as a "permanent outer wall" and a "replaceable inner wall", the two walls being bonded or tied together by interlapping but without interlocking of certain of the commercial bricks or tiles.

For convenience, the term "blocks" may be used as a term broad enough to include what is usually designated as brick and what is frequently designated as tile. In the permanent or outer wall portion, a great deal of common brick will usually be employed, but the inner or replaceable inner wall portion should be made up entirely of refractory or fire bricks or blocks.

In the accompanying drawings, which illustrate the invention, like characters indicate like parts throughout the several views.

Referring to the drawings:

Fig. 1 is a fragmentary perspective showing the improved wall with certain of the blocks removed to better illustrate the wall structure;

Fig. 2 is a fragmentary perspective with some of the blocks removed, illustrating a wall of the type of structure shown in Fig. 1, designed as a partition wall of the furnace;

Fig. 3 is a view corresponding to Fig. 1, but illustrating a slightly modified construction; and

Fig. 4 is a view corresponding to Fig. 2,

but illustrating the manner of incorporating the structure of Fig. 3 in a partition wall.

In the wall structure illustrated in Fig. 1, the permanent outer wall portion is shown as made up of common bricks 5, combined sill and lintel blocks 6, and column-forming blocks 7; and the inner or replaceable wall portion is shown as made up of standard fire bricks 8 and 8', and double length fire bricks 9. The above noted wall-forming elements, as already indicated, are of commercial size, such as found on the market. For example, the fire bricks 8 and 8' are approximately 2 $\frac{1}{2}$ x 4 $\frac{1}{2}$ x 9, the common brick are of slightly less dimensions than just noted, so as to allow for mortar, the double length fire bricks 9 are approximately 2 $\frac{1}{2}$ x 4 $\frac{1}{2}$ by 18, the combined sill and lintel-forming blocks 6 are approximately 5 x 13 $\frac{1}{2}$ x 18, and the column-forming blocks 7 are approximately 2 $\frac{1}{2}$ x 9 x 9. The common brick 5 are laid in the usual or any suitable way between horizontal layers of the combined sill and lintel-forming blocks 6, and the blocks 7 are laid in vertical tiers, so as to form columns that extend between and support the projecting portions of the blocks 6 and overlap the joints between the abutting ends of the latter. This arrangement forms large rectangular openings 10 between the laterally spaced columns 7 and between the vertically spaced blocks 6.

In laying up the inner or replaceable portion of the wall, the long or bonding bricks 9 are laid as "headers" within the rectangular wall openings 10 and are spaced apart by the intervening bricks 8 laid as "headers" and the bricks 8' laid as "stretchers." Approximately one-half of the long bricks 9 and all of the "stretcher" laid bricks 8' are within the wall openings 10, but the bricks 8 are outside of the said openings 10 and, in this preferred arrangement, terminate flush with the projecting ends of the long bonding bricks 9. In laying up the complete wall, the two wall portions may be laid simultaneously, or the permanent wall portion may be first laid and the replaceable wall portion thereafter laid.

It will now be noted that the replaceable inner wall is made up of horizontal belts of brickwork, which, at intervals, are built into the rectangular recesses of the outer wall structure, so that the two wall structures are securely bonded together. These

belts of brickwork are separated vertically only by the vertical spaces represented by the combined sill and lintel-forming blocks 6, and such spaces are filled in, in the particular arrangement illustrated in the drawing, each by two horizontal rows of the fire bricks 8 laid as headers and supported on the bonded belts. Here it will be further noted that the use of the blocks 6 as combined sills and lintels is important, for the reason that it leaves only vertically narrow spaces to be filled in by fire bricks laid as headers and which are not tied or bonded to the permanent wall. Of course, these latter noted bricks may be readily replaced at any time and, also, very considerable portions of the masonry belts themselves may be replaced without tearing down the whole or any large part of the replaceable wall structure. The long bonding bricks 9, when the bricks between the same are more or less removed, may be readily loosened and knocked out of the recesses 10 and thereafter replaced. The feature of using standard or commercial sizes of bricks or blocks to bond the horizontal belts of the replaceable wall to the permanent wall is obviously highly important, for it not only affords a cheap structure but a wall that may be primarily built up at a minimum of cost and which, moreover, may be repaired and maintained at a minimum cost.

The partition wall illustrated in Fig. 2 is of the same type of structure as that illustrated in Fig. 1, with the following exceptions: The permanent wall, in this structure, is the central wall and the replaceable portions of the wall are built on opposite sides of the central wall. The recesses 10^a extend completely through the permanent central wall and the ends of the long bonding bricks 9 extend completely through said recesses 10^a. However, as an important feature, the ends of the bonding bricks 9 of the one replaceable wall are extended into alternate recesses 10^a of each horizontal row, or, otherwise stated, the bonding bricks 9 that project from horizontally adjacent recesses 10^a project at opposite sides of the permanent wall. This arrangement gets the best kind of bonding between the center wall and the two replaceable walls and gives a maximum projection of said bricks 9 into or through the permanent wall.

In the wall structure illustrated in Fig. 3, the permanent wall is shown as of identically the same construction as that illustrated in Fig. 1, but the replaceable wall is of somewhat different construction. This replaceable wall is made up of ordinary fire bricks of standard size, indicated at 8^a and 8^b, and long bonding bricks 9^a. The bonding bricks 9^a are placed vertically edgewise and their ends are inserted into the rectangular recesses 10 and seated on the im-

mediately underlying combined sill and lintel-forming blocks 6. The horizontal belts, between the projecting ends of the long bonding bricks 9^a and between the vertical rows of the latter, are filled in by fire bricks 8^a, 9^c and 8^b, the former of which are bricks laid as headers and the latter of which are bricks laid as stretchers, and here it will be noted that the belts made up of the bricks 8^a, 9^c and 8^b are built into and complete the filling of the rectangular wall recesses 10, thereby affording a highly efficient bond between the permanent and the replaceable walls.

Fig. 4 shows a partition wall involving the type of structure illustrated in Fig. 3. In this wall structure, the permanent center wall is shown as of identically the same construction as that illustrated in Fig. 2, and in this design, the horizontal groups of long bonding bricks 9^a are inserted into alternate recesses 10 of the horizontal rows, so that adjacent groups of bricks 9^a project from the opposite sides of the permanent wall. The same advantages as to bonding that was attained in the structure illustrated in Fig. 2 is also attained in this structure. Fig. 4. The several structures here illustrated have this common advantage, that they may be constructed from standard size commercial bricks and without requiring any bricks or blocks of any peculiar or special design. Such blocks are not only cheaper than specially made blocks, but they may be secured almost any place where commercial fire bricks and the like are manufactured or carried in stock. Moreover, blocks or bricks of these commercial sizes may be rapidly laid and are less liable to crack under intense heat than are, for example, larger blocks, such as generally used in walls made up of or requiring specially designed blocks. All of the said commercial blocks, bricks or tiles are simple rectangular structures free from offsets, projections and the like.

In the constructions illustrated in Figs. 3 and 4, the replaceable brick belts may be built up entirely of standard size and double length bricks, but preferably, as the lower course, I use standard size 9 x 9, or square, bricks 9^c; and the horizontal spaces between the groups of long bonding bricks 9^a are filled in by relatively short bricks 9^b.

What I claim is:

1. A composite wall comprising a permanent wall structure and a replaceable wall structure, said permanent wall structure being formed with vertically and horizontally spaced rectangular recesses and having built therein horizontally disposed blocks that form sills for overlying recesses and lintels for underlying recesses, and said replaceable wall being made up of belts of relatively long and short bricks, said

long bricks extending from the replaceable wall into the recesses of said permanent wall.

2. A composite wall comprising a permanent wall structure and a replaceable wall structure, said permanent wall structure being formed with vertically and horizontally spaced rectangular recesses and having built therein horizontally disposed blocks 10 that form sills for overlying recesses and lintels for underlying recesses, and said replaceable wall being made up of belts of relatively long and short bricks, said long bricks extending from the replaceable wall 15 into the recesses of said permanent wall, and some of said short bricks being interposed between said long bricks within said recesses.

3. A composite wall comprising a permanent wall structure and a replaceable wall structure, said permanent wall structure being formed with vertically and horizontally spaced rectangular recesses and having built therein horizontally disposed blocks 25 that form sills for overlying recesses and lintels for underlying recesses, and said replaceable wall being made up of belts of relatively long and short bricks, said long bricks extending from the replaceable wall 30 into the recesses of said permanent wall, all of said wall-forming elements being simple rectangular commercial structures.

4. A composite wall comprising a permanent wall and a replaceable wall, said permanent wall having vertically and horizontally spaced rectangular recesses and said replaceable wall being made up of relatively long and short commercial rectangular bricks, the said long bricks being extended from the replaceable wall into the recesses of said permanent wall and some of the short bricks being laid within said recesses to fill the spaces between said long bricks.

45 5. A composite wall comprising a permanent wall and a replaceable wall, said permanent wall having vertically and horizontally spaced rectangular recesses and said replaceable wall being made up of relatively 50 long and short commercial rectangular bricks laid as headers in said replaceable wall, said long bricks being extended into the recesses of said permanent wall and some of the short bricks being laid as stretchers within said recesses to fill the spaces between said long bricks.

6. The structure defined in claim 1 in which the column-forming portions of the permanent wall between recesses are made up of flat rectangular blocks laid one upon the other, and the ends of the combined sill and lintel-forming blocks being interposed between vertically spaced groups of column-forming blocks. 60

7. The structure defined in claim 1 in which the recesses in the permanent wall extend completely through the same and in which there is a replaceable wall of the character described located on each side of said permanent wall, the projecting recess-engaging portions of the two replaceable walls being alternated in their engagement with said recesses. 70

8. The structure defined in claim 5 in which the recesses in the permanent wall extend completely through the same and in which there is a replaceable wall of the character described located on each side of said permanent wall, the projecting recess-engaging portions of the two replaceable walls being alternated in their engagement with said recesses. 75

9. The structure defined in claim 1 in which said long and short bricks have the same cross section but the long bricks are approximately twice the length of said short bricks. 80

10. The structure defined in claim 1 in which said long and short bricks have the same cross section but the long bricks are approximately twice the length of said short bricks, and in which the column-forming portions of said permanent wall are made up of flat square blocks having approximately the width and depth of the length of said short bricks. 90

11. The structure defined in claim 1 in which said long and short bricks have the same cross section but the long bricks are approximately twice the length of said short bricks, and in which the column-forming portions of said permanent wall are made up of flat square blocks having approximately the width and depth of the length of said short bricks, and in which the combined sill and lintel-forming blocks have approximately the same length measured horizontally along the wall as have said long bricks measured transversely of the wall. 100

In testimony whereof I affix my signature.
MICHAEL LIPTAK. 110
